CLAIM

The ornamental design for an auxiliary wiring device for an I/O module, as shown and described.

DESCRIPTION

FIG. 1 is an isometric view of an auxiliary wiring device for an I/O module showing our new design;

FIG. 2 is a bottom view of the auxiliary wiring device for an I/O module showing our new design;

FIG. 3 is a rear view of an auxiliary wiring device for an I/O module showing our new design;

FIG. 4 is a front view of an auxiliary wiring device for an I/O module showing our new design;

FIG. 5 is a top view of an auxiliary wiring device for an I/O module showing our new design;

FIG. 6 is a left side view of an auxiliary wiring device for an I/O module showing our new design; and,

FIG. 7 is a right side view of an auxiliary wiring device for an I/O module showing our new design.

Broken lines in the drawings are used to depict environment and do not form any part of the claimed design.
